US0D1071747S

(12) **United States Design Patent** (10) Patent No.: **US D1,071,747 S**
(45) Date of Patent: ** Apr. 22, 2025

(54) **THERMOSTAT**

(71) Applicant: **Trane International Inc.**, Davidson, NC (US)

(72) Inventors: **Jeffrey L. Stewart**, Whitehouse, TX (US); **Nathan Matney**, Davidson, NC (US); **Jonathan Hargrove**, Davidson, NC (US); **Melanie Fox**, San Francisco, CA (US); **Mark Edward Hearn**, San Francisco, CA (US); **Yale Franklin Shaw**, San Francisco, CA (US); **Ariel David Turgel**, San Francisco, CA (US)

(73) Assignee: **Trane International Inc.**, Davidson, NC (US)

(**) Term: **15 Years**

(21) Appl. No.: **29/789,647**

(22) Filed: **Oct. 8, 2021**

(51) LOC (15) Cl. **10-05**

(52) U.S. Cl.

USPC **D10/50**

(57) **CLAIM**

The ornamental design for a thermostat, as shown and described.

DESCRIPTION

FIG. 1 is a perspective view of a thermostat showing our new design.

FIG. 2 is a left elevation view of the thermostat of FIG. 1. FIG. 3 is a right elevation view of the thermostat of FIG. 1. FIG. 4 is a front elevation view of the thermostat of FIG. 1. FIG. 5 is a rear elevation view of the thermostat of FIG. 1. FIG. 6 is a top plan view of the thermostat of FIG. 1; and, FIG. 7 is a bottom plan view of the thermostat of FIG. 1. The broken lines shown are included for the purpose of illustrating portions of the thermostat and form no part of the claimed design.

1 Claim, 7 Drawing Sheets
